CHARLES E. ENNES, OF CHICAGO, ILLINOIS, ASSIGNOR TO OTIS ELEVATOR COMPANY, OF NEW YORK, N. Y., A CORPORATION OF NEW JERSEY.

MOTOR-CONTROLLING MECHANISM.

SPECIFICATION forming part of Letters Patent No. 738,173, dated September 8, 1903.

Application filed September 22, 1902. Serial No. 124,317. (No model.)

To all whom it may concern:

Be it known that I, CHARLES E. ENNES, a citizen of the United States, residing at Chicago, in the county of Cook and State of Illinois, have invented a new and useful Improvement in Motor-Controlling Mechanism, of which the following is a specification.

This invention relates to motor-controlling mechanism.

10 The object of the invention is to provide a motor-controlling mechanism which is simple in construction and efficient in operation.

15 A further object of the invention is to provide a controlling mechanism in which is combined a pressure medium and electrical devices for controlling the same.

20 A further object of the invention is to provide a switch mechanism actuated by hydraulic or other pressure, which pressure is controllable electrically or otherwise in any suitable manner.

Other objects of the invention will appear more fully hereinafter.

The invention consists, substantially, in the 25 construction, combination, location, and arrangement of parts, all as will be more fully hereinafter set forth, as shown in the accompanying drawings, and finally pointed out in the appended claims.

30 Referring to the accompanying drawings, and to the various views and reference-signs appearing thereon, Figure 1 is a view in elevation, parts in section, showing the mechanical construction and arrangement embodying the principles of my invention. Fig. 2 is an enlarged detail view in section on the line 2 2 of Fig. 1. Fig. 3 is a detail view of the switch for controlling the circuits of the electrical part of the apparatus employed in

35 connection with my invention. Fig. 4 is a detail view in section on the line 4 4 of Fig. 3. Fig. 5 is a view in diagram, illustrating the electrical action of the apparatus and the circuits controlled thereby.

40 The same part is designated by the same reference-sign wherever it occurs throughout the several views.

I will first describe the mechanical construction and arrangement illustrated in Figs. 45 1 to 4, inclusive, and afterward point out the

circuit connections controlled thereby and as indicated in Fig. 5.

Reference-signs A and B designate suitable chambers, suitably communicating with each other and with cylinders C and D. The cylinders C and D are of identical construction and arrangement, and therefore only one need be described. In each cylinder is arranged a piston E, the stem of which is connected to the core F of a solenoid G, so that when the solenoid is energized to move the core F thereof the piston-plunger E is moved longitudinally into the cylinder.

H designates a plunger or piston fitted to move in cylinder C and suitably connected to the piston-plunger E in any convenient manner—as, for instance, by means of a chain J.

K designates a spring interposed between the plunger H and the piston-plunger E, the tension of said spring tending to separate said plungers, the chain or other connection J preventing too far a separation of these parts.

A pipe L delivers from the end of the cylinders C D above the plunger H into chamber A and thence through a pipe or other connection M into chamber B. The chamber B communicates by a pipe or other connection N with a chamber O, and in the pipe or other connection N is arranged to operate a plunger P, arranged to control the delivery-mouths 80 of pipes Q, R, and S or the communications of said pipes with chamber B or pipe or other connection N.

A' B' designate cylinders in which operate plungers C' D', respectively. Each plunger is exposed on one face to the interior of chamber A and is connected, respectively, to switches E' F', which switches I designate "line-switches," the arrangement being such that when a pressure is imposed upon the face 85 of pistons C' D', which are exposed to the interior of chamber A, said switches are operated to close circuits between contacts a b and a' b', respectively. Similarly communicating with chamber B are cylinders G' H', 90 in which operate plungers J' K', suitably exposed on one face to the interior of chamber B and respectively connected to switches L' M', which switches I will designate "armature-switches," said switches coöperating with 95

contacts $a^2 b^2$, $a^3 b^3$, $a^4 b^4$, and $a^5 b^5$, arranged in pairs, as indicated.

Communicating with chamber O are cylinders N' O', in which operate plungers P' Q', respectively. Connected to plungers P' Q' are arms R' S', on which are supported contacts T' W'. Contact T' operates over resistance-blocks A², and the contact W' operates over resistance-blocks B². The inner face of each of the pistons P' Q' is presented toward the interior of chamber O.

Communicating with cylinder N' and at a point adjacent to its upper end is a pipe C², said pipe delivering into chamber O adjacent to the communication of cylinder O' therewith. In this pipe connection C² are arranged valves D² E², to which are connected operating-rods F² G², respectively, said rods being connected and projected by the movements of an arm H² J² or other movable part connected to move with the cores F of the magnet G G⁴; so that when either of said magnets G G⁴ is energized the corresponding rods F² G² are moved and valves D² E² are opened.

Arranged within chamber O are inwardly-opening valves, (indicated generally by reference-signs K² L²), suitable stops being provided to prevent the outward movement of said valves. The valve K² operates to close chamber O to cylinder N', while the valve L² operates to close chamber O to cylinder O', and the point of connection of pipe C² from cylinder N' is at a point between cylinder O' and valve L². The stops for valves K² L² and indicated, respectively, at 12 13, cause any pressure within chamber O to tend to maintain the valves closed. The valve K², however, as most clearly indicated in Fig. 2, is composed of a plate M², having holes or openings (indicated in dotted lines at N²) therethrough and which co-operates with a disk or plate O², having similar openings or holes P² therethrough, so that by suitably placing the plates M² O² to secure more or less registry of the openings P² and N² any desired degree of suitable pressure may be permitted to enter cylinder N' to operate the plunger P' therein. Similarly chamber B is provided with inwardly-opening valves Q² R², which operate when pressure is admitted to said chamber B to close said valves to prevent such pressure from being admitted from said chamber B to cylinders G' H' except through pipes Q and R, respectively, and which pipes communicate with pipe N through openings controlled by plunger P, which plunger is exposed to any pressure admitted to chamber B. In pipe Q is arranged a valve S², and in pipe R is arranged a valve T². These valves are so constructed and arranged that when they are both moved in one direction only one of them opens the passage it controls, and when they are both moved in the other direction only the other one opens the passage it controls. The operating-arms of these valves are connected together by a link A³, which is adapted to be engaged by cam-blocks B³ C³, re-

spectively, carried by rods F² G², and the arrangement is such that when magnet G is energized a rod F² is projected endwise. The cam-block B³ engaging link A³ causes valve S² to open to admit the pressure of an operating medium from chamber B to cylinder G' when the plunger P is shifted sufficiently to uncover the opening of pipe Q with pipe N, and whenever magnet G⁴ is energized to project rod G² cam-block C³ engages link A³ to open valve T², thereby opening communication of pipe R to cylinder H' whenever the plunger P opens the communication between cylinder N and pipe R. In the same manner a valve D³, opening inwardly, cuts off communication between cylinder B' and chamber A except through pipe S, the communication of which with the source of pressure is controlled by plunger P, as above explained. All of the plungers C', D', J', and K' when operated by the pressure-operating medium are moved in their respective cylinders against the action of suitable springs E³, which tend to return the same when the pressure is relieved. The valves K², L², Q², R², and D³ are all arranged to open inwardly, so that when the pressure imposed upon said valves is relieved said valves may readily open to permit the parts to return quickly to their initial positions.

Reference-sign A⁴ designates generally the operating-switch and comprises an arm B⁴, carrying a contact-piece C⁴, insulated therefrom, and also a contact-piece D⁴, which is in electrical connection with arm B⁴. Contact-block C⁴ is arranged to co-operate with contact-strips c d d', so as to complete electrical circuits between strip c and strip d when moved in one direction and to complete circuit between strips c and d' when moved in the other direction, and contact-block D⁴ co-operates with contacts d² d³ when moved in one direction and with contacts d⁴ d⁵ when moved in the other direction. This contact-block D⁴ should be of sufficient length to bridge all the space between contacts d² d³ or contacts d⁴ d⁵.

The pipes L and M and chambers A and B are adapted to contain or to receive any suitable pressure medium—such, for instance, as water, alcohol, glycerin, or the like—and similarly pipe N and chamber O are adapted to receive an operating or pressure medium. I prefer to employ glycerin for this purpose because of its permanency and freeness from evaporation.

The mechanical operation is as follows: When solenoid G is energized, the core F thereof is drawn into the coil of said solenoid, thereby projecting piston-plunger E and through the spring K moving plunger H in cylinder C, and consequently imposing a pressure upon the pressure medium contained in the pipes and chambers. This pressure being transmitted through chamber A to plunger C' in cylinder A' actuates the line-switch M to close the circuit between contacts a b.

At the same time pressure imposed upon the operating medium causes plunger P to be forced through pipe N, so as to uncover the opening of pipe Q with pipe N and also the opening of pipe S with pipe N and of pipe R with pipe N. The energization of magnet G causes a projection of rod F² and by reason of the engagement of cam-block B³ with link A³ shifts valve S² into position to open pipe Q, so that the pressure-operating medium is shifted to pass from pipe N through pipe Q and into chamber B at a point to expose piston J' thereto, thereby causing the armature-switch L' to be actuated to close circuit between contacts a² b² and a³ b³ and at the same time to admit pressure through pipe S into cylinder B' to actuate plunger D', thereby actuating switch F', which I have designated the "brake-switch," to close circuit between contacts a' b'. The projection of plunger P through pipe N also forces the operating medium through the graduated or adjustable apertures of valve K² into cylinder N' and causes plunger P' to gradually or slowly move through cylinder N', thereby raising arm R' and causing contact T' to travel over the resistance contacts or blocks A². The movements of rod F² under the conditions above described, while effecting an operation of valve D², does not supply the pressure medium from cylinder N' through pipe C² to cylinder O' when plunger P' has been moved a sufficient height or distance to uncover the communication of pipe C² with cylinder N', because the valve E², which also controls pipe O², has not been opened under the conditions above set forth. Consequently the above operation places the apparatus in what I shall term the position of "slow speed," the various parts and switches operated as described serving to complete the desired circuit connections for a slow speed, as will presently be more fully explained in connection with the operation of the apparatus. The above operation, it will be observed, leaves the armature-switch M' in its initial or original position. Consequently the motor will operate in one direction, as the armature-switch L' controls the motor-circuits for operation in one direction and the switch M' controls the motor-circuits for the motor to operate in the opposite direction, as will be more fully explained. In order to attain a high speed, the magnet or solenoid G⁴ is energized, thereby operating the core F thereof and projecting rod G² and opening valve E², and consequently admitting pressure through pipe C² to cylinder O' and operating plunger Q', thereby causing contact W' to cut out the remaining resistance controlled by resistance blocks or contacts B². If solenoid G has been previously energized, as above explained, this action of solenoid G⁴ will not effect an operation of valve T². Consequently the motor will continue to run in the direction as controlled by armature-switch L'. If, however, magnet G⁴ is energized first, then valve T² will be opened.

and armature-switch M' will be actuated to control the motor-circuits to cause the same to revolve in the opposite direction, and a subsequent energization of magnet G will not effect this direction, and in any event, whether magnet G or G⁴ is energized first, the slow-speed resistance controlled by piston P' will first be cut out, and the high-speed resistance controlled by contact-blocks B² will not be cut out until both magnets G G⁴ are energized. When the magnets G G⁴ are de-energized, the cores F return by gravity or otherwise to the initial positions thereof, as indicated in Fig. 1, thereby causing the piston-plungers E to draw or carry with them the plungers H, thereby relieving the pressure on the operating medium and creating some degree of vacuum or suction, and the inwardly-opening valves D², Q², R², K², and L² permit the operating medium to quickly exhaust or be restored to original condition, the parts to be restored to their initial positions. When the solenoid-cores F are drawn into the solenoid-coils, circuit is closed between contacts f' f' and f² f² by arms H² J² or otherwise and for a purpose presently to be described.

Having now explained the mechanical construction and operation, I will now describe the electrical connections and operation, reference being had to Fig. 5. With the parts in the position shown in Figs. 1 and 5, suppose the operating switch-arm B⁴ is moved to the right for contacts or strips D⁴ d² to be brought into electrical connection with each other. Thereupon the following circuit is completed: from main supply-wire A⁷ to contact a, wire 20, contact c, through contact-block C⁴ to contact d, through wire 21, the coils of magnet G, wire 22, contact d², contact D⁴, arm B⁴, wire 23 to the return-wire B⁷, thereby energizing magnet G and causing piston-plunger E to be operated and a pressure to be imposed upon the pressure medium, thereby actuating line-switch-operating plunger C' and causing said switch to close or bridge contacts a b. At the same time the armature-switch L' is actuated through the mechanical operation above described, thereby closing circuit between contacts A² and B² and also between contacts A³ and B³. Thereupon the following circuits are completed: from main supply-wire A⁷ to contact a, through the line-switch E' to contact b, wire 24, the shunt field-wire 25 to main return-wire B⁷; also, the following circuit: from main supply-wire A⁷, contact a, wire 26, all of resistances A², wire 27, all of resistance B², wire 28, the series field-wire 29, contact b², contact a², wire 30, contact a⁵, wire 31, through the motor-wire 32, contact a⁴, wire 33, contact b³, contact a³, wire 34 to the return, thereby starting up the motor with the shunt field, the series field, and all the resistances in circuit. The actuation of brake-switch F', which takes place at the same time as the closing of armature-switch L', as above explained, causes the circuit to

be bridged from contact a' to contact b' . Thereupon the brake-magnet circuit is completed as follows: from main supply-wire A^7 , contact a , contact b , contact a' , switch F' , 5 contact b' , brake-magnet, wire 35 to return B^7 . The admission of the pressure to cylinder N' under the conditions noted actuates piston P' and gradually cuts out the resistances A^2 , which I have designated the 10 "slow-speed" resistance in Fig. 5, and the motor continues to operate at slow speed with shunt and series field and armature in operating circuit and with the brake-magnet energized to release the brake. In order to attain 15 high speed, the operating switch-lever B^4 is moved to the right sufficiently far to enable the contact D^4 to bridge the space between contacts d^3 and d^2 . Thereupon the circuit condition above described remains the 20 same; but in addition the current passing through contact d^2 divides, part passing therethrough contact-block D^4 , switch-arm B^4 , and wire 23 to return, and the other passing from block D^4 to contact d^3 , wire 36, magnet G^4 , 25 wire 37, contact f' , and thence across the space to contact f , when the core of solenoid G has been sufficiently energized to permit arm H^2 to bridge the space between contact f' and contact f , and thence through wire 38, wire 30 23, and to return. Thereupon without derangement of any of the apparatus, as above explained, magnet G^4 is energized, thereby causing rod G^3 to be moved endwise and opening valve E^2 in pipe C^2 , and since valve 35 D^2 in the same pipe has previously been opened by the energization of magnet G it will be seen that pressure from cylinder N' is admitted through pipe C^2 to cylinder O' , thereby actuating plunger D' therein and effecting a cutting out of the resistances B^2 , which I have marked the "high-speed" resistance, and the motor operates at high speed. If magnet G^4 had been energized first, the 40 only difference in the operation from that above described would be that armature-switch M' would have been actuated instead of armature-switch L' , and this would have merely reversed the direction of current through the motor. Upon return of the operating-switch B^4 to central position the circuits of solenoids G G^4 are broken. The cores of said solenoids are thereupon permitted to return to initial position, effecting a re-organization of all the parts. 45

55 It is believed that the construction and operation of the apparatus shown and described and embodying the principles of my invention will be fully understood from the foregoing description.

60 It is obvious that many variations and changes in the details of construction and arrangement would readily occur to persons skilled in the art and still fall within the spirit and scope of my invention. I do not desire, therefore, to be limited or restricted to the exact details shown and described; but,

Having now set forth the object and nature

of my invention and a construction embodying the principles thereof, what I claim as new and useful and of my own invention, and desire to secure by Letters Patent, is—

1. In a motor-controlling mechanism, a switch, pressure mechanism for operating the same, and electrical devices for controlling the pressure of the operating medium, said electrical devices also operating to control the supply of said medium to said mechanism, as and for the purpose set forth. 75

2. In a motor-controlling mechanism, a pressure-operating switch-actuating mechanism, and electrically-operated means for controlling the pressure of the operating medium and its supply to said mechanism, as and for the purpose set forth. 80

3. In a motor-controlling mechanism, a switch-actuating pressure mechanism including a cylinder, a piston operating therein, and electrical devices for controlling the pressure of the operating medium, said devices operating to control the supply of said medium to the cylinder to move said piston in one direction, as and for the purpose set forth. 85

4. In a motor-controller, switch-actuating pressure mechanism normally inactive with respect to the switch, and electrical devices for controlling the pressure of the operating medium and its supply to said pressure mechanism, as and for the purpose set forth. 90

5. In a motor-controller, switch-actuating pressure mechanism, electrical means for controlling the pressure of the operating medium and its supply to said mechanism to operate the switch in one direction, and devices for restoring the switch to normal position, as and for the purpose set forth. 100

6. In a motor-controller, switch-actuating pressure mechanism including a cylinder, a piston operating in said cylinder, pressure-pipes containing a fixed quantity of operating medium and communicating with said cylinder, means for normally maintaining said piston in one limit of its movement, and electrical devices for moving said piston to vary the pressure of said operating medium, as and for the purpose set forth. 105

7. In a motor-controller, switch-actuating pressure mechanism including a system of pipes adapted to contain a fixed body of operating medium, a cylinder opening to said pipes, a piston operating in said cylinder, and electrical devices for operating said piston to effect a movement of said body of operating medium, as and for the purpose set forth. 110

8. In a motor-controlling mechanism, a series of switches, plungers or pistons connected to said switches for operating the same, a pressure mechanism for actuating said plungers, and including pipes or chambers adapted to contain a fixed body of operating medium, said pipes delivering to said piston, and means for moving said piston to shift the pressure medium in said pipes, as and for the purpose set forth. 125

9. In a motor-controlling mechanism, a

- switch, a plunger connected thereto for operating the same, a pressure mechanism for actuating said plunger, and including pipes or chambers adapted to contain a fixed body of operating medium, said pipes delivering to said piston and electrical devices for moving said piston to control the pressure of said operating medium, as and for the purpose set forth. 5
10. In a motor-controlling mechanism, a switch, means normally operating to open said switch, a pressure mechanism for closing said switch, including a system of pipes and chambers adapted to contain a fixed body of operating medium and means for controlling the pressure of said medium, as and for the purpose set forth. 15
11. In a motor-controlling mechanism, a switch, means normally tending to maintain said switch open, pressure mechanism for closing said switch, including a system of pipes and chambers adapted to contain a fixed body of operating medium and electrical devices for controlling the pressure of the medium in said pipes and chambers, as and for the purpose set forth. 20
12. In a motor-controlling mechanism, a switch, a plunger connected to said switch for operating the same, a cylinder in which said plunger operates, a pressure mechanism for operating said plunger in one direction including a system of pipes and chambers adapted to contain a fixed body of operating medium, means for normally opposing the pressure of said medium, and electrical devices for imposing a pressure upon said medium, as and for the purpose set forth. 25
13. In a motor-controlling mechanism, a series of switches, pressure mechanism for actuating said switches including a system of pipes and chambers adapted to contain a fixed body of operating medium, and means for controlling said pressure mechanism to actuate said switches in successive order, as and for the purpose set forth. 30
14. In a motor-controlling mechanism, a series of switches, means normally operating to maintain said switches in open position, pressure mechanism for operating said switches including a system of pipes and chambers adapted to contain a fixed body of operating medium, and devices for controlling the pressure-operating medium in said pipes to successively operate said switches, as and for the purpose set forth. 35
15. In a motor-controlling mechanism, a line-switch and an armature-switch, pressure mechanism for actuating said switches, and means for controlling said pressure mechanism to operate said line-switch in advance of the operation of said armature-switch, as and for the purpose set forth. 40
16. In a motor-controlling mechanism, a line-switch and an armature-switch, pressure mechanism for actuating said switches, electrical devices for controlling said pressure mechanism to actuate said line-switch, and means actuated by said electrical devices for admitting the pressure to actuate said armature-switch after said line-switch is operated, as and for the purpose set forth. 45
17. In a motor-controlling mechanism, a line-switch and a brake-switch, pressure mechanism for actuating said switches, and electrical devices for controlling said pressure mechanism to actuate said line-switch in advance of the actuation of said brake-switch, as and for the purpose set forth. 50
18. In a motor-controlling mechanism, a line-switch, a brake-switch and an armature-switch, pressure mechanism for operating all of said switches, and electrical devices for controlling said pressure mechanism to actuate said line-switch in advance of the actuation of said brake and armature switches, as and for the purpose set forth. 55
19. In a motor-controlling mechanism, a line-switch and armature-switches, said armature-switches arranged, when actuated, to control the direction of current through the armature, pressure mechanism for actuating said switches, and electrical devices for controlling said pressure mechanism to actuate either of said armature-switches at will and said line-switch in advance of the actuation of said armature-switches, as and for the purpose set forth. 60
20. In a motor-controlling mechanism, a line-switch, armature-switches for controlling the direction of current through the armature, a resistance-controlling device, pressure mechanism for actuating said switches and devices, and electrical devices for controlling said pressure mechanism, as and for the purpose set forth. 65
21. In a motor-controlling mechanism, switches arranged to control the motor-circuits, resistance-controlling devices arranged in the motor-circuits, plungers for respectively operating said switches and resistance-controlling devices, pressure mechanism for actuating said several plungers, and electrical devices for controlling said pressure mechanism, as and for the purpose set forth. 70
22. In a motor-controlling mechanism, a plurality of switches, a pressure mechanism for actuating said switches, electrical devices for controlling said pressure mechanism, and inwardly-opening valves whereby said pressure mechanism is enabled to quickly restore the parts to normal position, as and for the purpose set forth. 75
23. In a motor-controlling mechanism, a system of pipes arranged to receive a pressure medium, means for imposing pressure upon said medium, and inwardly-opening valves arranged in said pipes and operating to permit the restoration of the parts to normal position upon withdrawal of the pressure imposed upon said medium, as and for the purpose set forth. 80
24. In a motor-controlling mechanism, a series of switches, a pressure mechanism including a series of pipes, plungers communi-

eating with said pipes, said pipes adapted to receive a pressure medium, means for imposing a pressure upon said medium to operate said plungers, and inwardly-opening valves whereby when said pressure is removed the parts are quickly restored to normal position, as and for the purpose set forth.

25. In a motor-controlling mechanism, a series of switches, plungers for operating the same, pipes to which said plungers are exposed, said pipes adapted to receive a pressure-operating medium, means for imposing a pressure upon said medium, valves arranged in said pipes, by-passes around said valves, and means for controlling said by-passes, as and for the purpose set forth.

26. In a motor-controlling mechanism, resistances arranged in the motor-circuit and in sets, a plunger for controlling each set, a pressure mechanism for actuating said plungers, and means for controlling said pressure mechanism to actuate the plunger of one set of resistance devices in advance of the other, as and for the purpose set forth.

25 27. In a motor-controlling mechanism, resistances arranged in sets, a plunger for controlling each set of resistances, a cylinder in which each plunger operates, a pipe communicating from one of said cylinders to the other, valves arranged in said pipe connection, a pressure mechanism for actuating said plungers including a pressure-medium-containing chamber, means for creating a pressure in said chamber, said chamber communicating with one of said cylinders, and means for controlling said valves, whereby both of said plungers may be actuated successively, as and for the purpose set forth.

28. In a motor-controlling mechanism, a rheostat arranged in the motor-circuit, a plunger for actuating said rheostat, a cylinder in which said plunger operates, a chamber adapted to contain a pressure medium, a valve arranged to control the communication of said chamber and cylinder, means for imposing a pressure upon the operating medium contained in said chamber, and means for adjusting said valve to vary the speed at which said pressure medium is admitted to said cylinder, as and for the purpose set forth.

29. In a motor-controlling mechanism, a plurality of switches arranged to control the motor-circuits, a pressure mechanism for actuating said switches and including a chamber, a pair of cylinders communicating with said chamber, a piston operating in each cyl-

inder, electrical devices for operating either of said pistons at will, whereby when either of said pistons is operated a pressure is imposed upon the pressure medium contained in said chamber, valves controlled by said electrical devices for admitting said pressure medium to one or another of said switches according to which electrical device is in operation, all combined and arranged as and for the purpose set forth.

30. In a motor-controlling mechanism, a line-switch, an armature-switch and a rheostat, a pressure mechanism for actuating said switches and rheostat and including a chamber adapted to contain a pressure medium, valves for controlling the supply of operating medium to said armature-switch and rheostat, means for imposing a pressure upon the operating medium in said chamber, and means actuated coincidently therewith for operating said valve, as and for the purpose set forth.

31. In a motor-controlling mechanism, a line-switch, armature-switches and a rheostat, a pressure mechanism for actuating said switches and rheostat including a chamber adapted to receive a pressure medium, valves for controlling the supply of said medium to actuate said armature-switch and rheostat, a rod for operating said valves, electrical devices for imposing a pressure upon the medium contained in said chamber, said electrical devices operating, when operated, to actuate said rod, as and for the purpose set forth.

32. In a motor-controlling mechanism, a line-switch, armature-switches for controlling the direction of current through the armature, a brake-switch and a rheostat, pressure mechanism for operating said several switches and rheostat and including a chamber adapted to receive a pressure medium, valves for controlling the supply of said medium to said armature-switches and rheostat, a pair of solenoids each adapted, when energized, to impose a pressure upon said medium, and means actuated by said solenoids for operating said valves, all combined and arranged as and for the purpose set forth.

In witness whereof I have hereunto set my hand, this 18th day of September, 1902, in the presence of the subscribing witnesses.

CHARLES E. ENNES.
